UNITED STATES PATENT OFFICE

JOHN H. SHAW, OF NEW HAVEN, CONNECTICUT, ASSIGNOR TO SARGENT & COMPANY,
OF NEW HAVEN, CONNECTICUT

LOCK KEY

Application filed May 17, 1928. Serial No. 278,543.

My invention relates to improvements in lock keys, and more especially to keys intended for use in pin tumbler lock mechanisms or the like.

5 A primary object of my invention is to provide a key which may be suitable for use with a pin tumbler lock mechanism, and which is adapted to operate such a mechanism when inserted to a plurality of 10 different depths.

A further object of the invention is to provide a key having means thereon for aligning the pin tumblers or the like of a lock mechanism in which the key may be 15 moved axially in the lock mechanism while maintaining the pin tumblers in the same position of alignment.

It is highly desirable in certain instances to provide cylinder or other lock mechanisms which may be readily disassembled from a lock case in order that the combination of the lock may be changed, or for other purposes. It has been proposed heretofore to provide a secondary locking system 25 for securing the key plug and pin tumbler mechanism in the lock case, this secondary locking mechanism being under the control of a key which, under ordinary or normal conditions, will operate the locking mechanism in the normal manner to withdraw a latch bolt or the like and in which the key may be inserted to a different depth to unlock the secondary locking mechanism, whereupon the key plug and pin tumbler

35 mechanism may be withdrawn from the lock case. Prior locks of this type have been provided with pin tumblers having a plurality of breaks or shears therein. Upon the insertion of a proper key, one set of these breaks or shears is brought into alignment with the outer surface of the key plug to permit rotation thereof in withdrawing a latch bolt, etc. Upon the insertion of a different key, or of a further insertion of the same key, another set of breaks is brought into alignment in the secondary locking system to permit the lock mechanism to be withdrawn from the lock case.

50 In my co-pending application, Serial No.

278,545 filed May 17, 1928, I have disclosed a form of lock mechanism which may be readily disassembled from the lock case in order to change the combination thereof, and in which the disassembling of the lock mechanism from the lock case is under control of a key. In the preferred form of the invention disclosed in the above co-pending application there is but a single set of breaks or shears provided in the pin tumbler mechanism and the operation of the secondary locking mechanism is controlled by the depth of insertion of the key rather than a different combination or arrangement of the pin tumbler mechanism. The key of the present application is particularly adapted for use in such a lock.

55 In a more specific aspect, the present invention contemplates a key provided with a bit having notches therein which are substantially longer than the notches heretofore provided in similar keys.

60 To these and other ends, the invention consists in the novel features and combination of parts to be hereinafter described and 65 claimed.

65 Referring to the drawings,

70 Fig. 1 is an elevational view of a lock case containing a lock suitable for use in connection with my improved form of key; 75

Fig. 2 is an end view of the same;

75 Fig. 3 is a sectional view taken along line 3—3 of Fig. 2;

80 Fig. 4 is a sectional view taken along line 4—4 of Fig. 2;

85 Fig. 5 is a plan view of my improved form of key; and

90 Fig. 6 is a sectional view along line 6—6 of Fig. 3.

I will now describe my invention in connection with the preferred embodiment thereof shown in the drawings and in connection with the lock shown therein which is illustrative of one of the uses that may be made of my improved form of key. The lock mechanism shown is described and claimed in my copending application, Serial No. 278,545 filed May 17, 1928, and therefore it will be understood that the features relative to the improved form of locking

mechanism are claimed in the co-pending application and not herein.

Referring now to the drawings, the reference numeral 7 indicates in general a part 5 of a door lock comprising a door handle or knob 8 connected by means of a shank 9 to any usual or preferred form of latch bolt, or other lock mechanism, not shown herein, handle 8 having mounted therein a cylinder 10 lock case 10, having a plurality of radially projecting ribs or lugs 11 received within and seated at the bottoms of openings 12 in handle 8, handle 8 being provided with a face plate 13 bearing against an outer face 14 of lock case 10. Face plate 13 is provided on its periphery with interrupted threads 15 engaging similarly interrupted threads 16 in handle 8 and is normally locked against rotary movement relative to 15 handle 8 by plunger 17 in lock case 10, plunger 17 being urged towards plate 13 by a spring 18, plate 13 being provided with an opening 19 in which the plunger is normally seated while at the opposite end of 20 plunger 17 is a disk 20 received in an opening 21 in handle 8. The lock case 10 is provided with the usual key plug 22 having at one end thereof a thimble 23 extending into shank 9 and engaging a square rod 24 25 which may extend into a latch bolt or other lock mechanism carried in or on a door, and which is not shown herein. The usual pin tumblers 25 are provided to prevent rotation of key plug 22 except upon the insertion of a proper key. My improved form 30 of key which is indicated in general by the reference numeral 26 comprises the usual finger piece 27 and bit 28, the upper edge 29 of which, as viewed in Fig. 5 of the 35 drawings, is provided with notches 30, in order to properly align the pin tumblers and shoulders 31 which limit the amount 40 that the key may be inserted in the key 45 plug. In order that key 26 may properly align the pin tumblers 25 in a plurality of 50 positions, each pin tumbler engaging portion or notch 30 of key 26 is made of substantially greater length than in the usual key, as may be seen from Fig. 5 of the drawings.

The operation of the form of lock mechanism shown in the drawings when used with my improved form of key is as follows: The slot for the key will be in a vertical 55 position, or such other position as it may occupy when the key plug is held against rotation by the pin tumblers. The key is inserted into the slot until it occupies the position shown in Fig. 3, that is, a position 60 in which the shoulders 31 are spaced a substantial distance from the outer face of the key plug. In this position, the notches 30 on the bit 28 of the key bring the breaks in the pin tumblers into alignment with the 65 outer surface of the key plug, whereupon

the key plug may be rotated into the position indicated in dotted lines in Fig. 2. The key may now be fully inserted into the key plug, as shown in Fig. 4, bringing the end of the bit 28 into engagement with the disk 20 and withdrawing the plunger 17 from opening 19 in face plate 13, whereupon the latter may be rotated to bring the threads 15 opposite the interrupted portions of the threads 16 and the face plate and lock mechanism withdrawn in an axial direction from the handle 8. A lock mechanism having a different arrangement of tumblers therein may be placed in the handle 8 in place of the former locking mechanism and face plate 13 70 assembled on the handle 8, and rotated into position wherein the plunger 17 engages the opening 19, whereupon the face plate and lock mechanism are secured in the handle 75 against displacement, except in the manner 80 previously described.

From the foregoing description of my improved form of key and its use in connection with the lock mechanism shown, it will be readily understood that I have provided 90 a form of key which may engage a lock in a plurality of positions and operate the same. It will be further understood that although I have described but a single use 95 that may be made of my key that the same is not limited to such a use but may be used as a master key or in other ways, in which it is desirable to operate a lock mechanism by the same key inserted to a plurality of different depths.

While I have shown a preferred embodiment of my invention, it is to be understood 100 that the same is not to be limited to all the details shown, but is capable of modification and variation within the spirit of the invention and the scope of the appended 105 claims.

What I claim is:

1. A key for a lock having tumblers and a key engageable locking device positioned 110 beyond the tumblers, said key being provided with means for aligning said tumblers in one position thereof and being adapted to be moved to another position without displacing the alignment of said tumblers, and means on the key for operating the key engageable locking device upon movement of the key into the last named position.

2. A key for a lock having a series of 120 tumblers adapted to be moved to releasing position by the key and a separate locking device also movable to releasing position by the key, said key being insertable in the lock to one depth to move the tumblers into releasing position and to another depth to move said other locking device to releasing position, the bit of said key being provided 125 with relatively long tumbler engaging surfaces adapted to maintain the tumblers in 130

the same position of alignment when moved from one depth to the other.

3. A key for a lock provided with a series of tumblers adapted to be moved to releasing position by the key and provided with a separate locking device also adapted to be operated by the same key, said key being provided with means to move the tumblers to releasing position when inserted into the lock to a given depth, and provided with means to align said tumblers in the same releasing position when inserted to a different depth, said key being provided with means adapted to operate said separate locking device when standing in said last named position.

4. A key for a lock having a series of tumblers adapted to be moved by the key to a releasing position, and having a separate locking device also adapted to be moved by the key to releasing position, said key being adapted to be inserted into the lock to two different depths and being provided with means to move the tumblers to releasing position when standing in either position, and said key being provided with means for engaging and actuating said second locking device in one position but being disengaged therefrom in the other position.

5. A key for a lock having a series of locking tumblers adapted to be moved to releasing position by the insertion of the key, and a separate locking device adapted to be moved to releasing position by a further movement of the key, said key being provided with a bit cut to move the tumblers to releasing position and to permit a further movement of the key to a second position without disturbing the tumblers, said key being provided with means adapted to operate said separate locking device when in said second position.

6. A key for a lock having a series of locking tumblers adapted to be moved to releasing position by the insertion of the key therein to one depth, and a separate locking device adapted to be moved to releasing position by the insertion of the key to another depth, said key being provided with means to move the tumblers to releasing position when inserted to said first depth and adapted to be moved to the position of said second depth without displacing the tumblers, and being provided with means adapted to operate said separate locking device when inserted to said second depth.

In witness whereof, I have hereunto set my hand this 9 day of May, 1928.

JOHN H. SHAW.
